UNITED STATES PATENT OFFICE.

THEODORE F. SMYTHE, OF PHILADELPHIA, PENNSYLVANIA.

DESIGN FOR A RACK FOR TOILET ARTICLES, JEWELRY, &c.

SPECIFICATION forming part of Design No. 29,614, dated November 8, 1898.

Application filed October 12, 1898. Serial No. 693,352. Term of patent 3½ years.

To all whom it may concern:

Be it known that I, THEODORE F. SMYTHE, a citizen of the United States, residing in the city and county of Philadelphia, State of Pennsylvania, have invented and produced a new and original Design for a Rack for Toilet Articles, Jewelry, &c., of which the following is a specification, reference being had to the accompanying drawings, forming part thereof.

The leading feature of my design for a rack for toilet articles, jewelry, &c., is, first, a body of the form of an artist's palette and supporting devices thereon, and, next, a bracket rearward of the thumb-opening, constituting a support for a perfumery or other toilet bottle.

Figure 1 represents a perspective view of the obverse of a rack for toilet articles, jewelry, &c., embodying my design. Fig. 2 represents a section of a portion on line *xx*, Fig. 1.

In the drawings, A designates the body of the rack for toilet articles, jewelry, &c., the same being of the form of an artist's palette. On the obverse or face of the body are the 25 hooks B B and the case or receptacle C.

D designates a bracket on the reverse rearward of the thumb-opening E. The body has legs F and a prop G, simulating the appearance of an easel.

Having described my invention, what I claim as new, and desire to secure by Letters Patent, is—

The design for a rack for toilet articles, jewelry, &c. substantially as shown and described.

THEODORE F. SMYTHE.
